(57) **CLAIM**

The ornamental design for an antimicrobial cladding for door pull, as shown and described.

DESCRIPTION

FIG. 1 is a front perspective view of a first embodiment of an antimicrobial cladding for door pull made in accordance with the present design, shown in environmental use; FIG. 2 is a front perspective view of the first embodiment of the antimicrobial cladding for door pull; FIG. 3 is a rear perspective view thereof; FIG. 4 is a left side view thereof; FIG. 5 is front view thereof; FIG. 6 is a right side view thereof; FIG. 7 is a back view thereof; FIG. 8 is a top plan view thereof; FIG. 9 is a bottom plan view thereof; FIG. 10 is an exploded perspective view of FIG. 1; FIG. 11 is a front perspective view of a second embodiment of an antimicrobial cladding for door pull made in accordance with the present design, shown in environmental use; FIG. 12 is a front perspective view of the second embodiment of the antimicrobial cladding for door pull; FIG. 13 is a rear perspective view thereof; FIG. 14 is a left side view thereof; FIG. 15 is a front view thereof; FIG. 16 is a right side view thereof; FIG. 17 is a back view thereof; FIG. 18 is a top view thereof; FIG. 19 is a bottom view thereof; and, FIG. 20 is an exploded perspective view of FIG. 11. The broken lines in the figures depict environment that forms no part of the claimed design. The claim is shown with a symbolic break in its length. The appearance of any portion of the article between the break lines forms no part of the claimed design.

1 Claim, 12 Drawing Sheets
